UNITED STATES PATENT OFFICE.

JAMES J. CONNELL, OF DETROIT, MICHIGAN.

BILLIARD-CUE TIP.

1,230,122.

Specification of Letters Patent. Patented June 19, 1917.

Application filed January 26, 1917. Serial No. 144,747.

To all whom it may concern:

Be it known that I, JAMES J. CONNELL, citizen of the United States, residing at Detroit, county of Wayne, State of Michigan, 5 have invented a certain new and useful Improvement in Billiard-Cue Tips, and declare the following to be a full, clear, and exact description of the same, such as will enable others skilled in the art to which it pertains 10 to make and use the same, reference being had to the accompanying drawings, which form a part of this specification.

My invention relates to tips for billiard cues shown in the accompanying drawings 15 and more particularly pointed out in the following specification and claims.

One object of this invention is to provide a cue tip of such construction that the use 20 of chalk may be eliminated as commonly employed to prevent the cue from glancing over the surface of a ball when playing.

Another object is to provide a tip which is not apt to be accidentally detached from the end of a cue.

25 Another feature of the invention is the peculiar construction and composition of the tip itself, the same consisting of both hard and relatively soft rubber elements.

With the foregoing and other objects in 30 view which will appear as the description proceeds, the invention resides in the combination and arrangement of parts and in the details of construction hereinafter described and claimed, it being understood that 35 changes may be made in the precise embodiment of the invention herein disclosed without departing from the spirit of the same.

In the accompanying drawings forming part of this specification,

40 Figure 1 is a longitudinal vertical sectional view of the tip showing a cue in dotted lines.

Fig. 2 is an end elevation of the tip.

Referring now to the letters of reference 45 placed upon the drawings,

A, denotes a cue. B, indicates a rubber thimble formed of hard rubber;—into the open end of which the cue projects,—the end of the latter being smaller in diameter

than the surface of the cue and thimble may 50 be flush with each other when in assembled relation.

Projecting from the end of the thimble is a slightly tapering stem B', on which is sleeved a relatively soft rubber tip C, the 55 inner wall of which is slightly funnel-shaped as indicated at C', to receive the cone-shaped end B², of the thimble. This form of construction provides a relatively longer abutting bearing surface between the 60 hard and soft rubber elements, than would be the case if the surfaces were at right angles to the longitudinal axis of the cue. Another advantage gained by this construction is that the shock caused through the 65 impact of the cue with the ball in striking the latter either above or below the axis of the ball is received against a relatively broad surface at substantially right angles to the line of force, which serves to increase 70 the accuracy of the shot.

While I prefer to employ rubber in the construction of the device—fiber or other suitable material may be used if desired.

Having thus described my invention what 75 I claim is:—

1. In a device of the character described, a thimble formed of substantially hard rubber adapted to receive the end of a cue, having an outwardly projecting stem, and an 80 annular rubber tip formed of relatively soft rubber mounted upon said stem.

2. In a device of the character described, a thimble formed of substantially hard rubber provided with an outwardly projecting 85 tapering stem, and a rubber tip of relatively soft rubber having a tapering hole to receive said stem.

3. In a device of the character described, a thimble having a projecting tapering stem 90 with a cone-shaped wall surrounding its base, and an annular tip sleeved upon said stem, having a funnel-shaped formation adapted to abut with the cone shaped wall of the thimble surrounding the base of the 95 stem.

4. In a device of the character described, a thimble formed of substantially hard rub-

ber having a projecting tapering stem with a cone-shaped wall surrounding its base, and an annular soft rubber tip sleeved upon said stem, having a funnel-shaped formation adapted to abut with the cone shaped wall of the thimble surrounding the base of the stem.

In testimony whereof, I sign this specification in the presence of two witnesses.

JAMES J. CONNELL.
